(57) **CLAIM**

The ornamental design for a wind generator wire frame, substantially as shown and described.

DESCRIPTION

FIG. 1 is a perspective view of a wind generator wire frame, showing my new design from the top and front, and part of the bottom;

FIG. 2 is a perspective view of the FIG. 1 generator, showing one side thereof, the opposite side being the same; and,

FIG. 3 is a perspective view of the FIG. 1 generator showing the top and front and part of the opposite side.

1 Claim, 2 Drawing Sheets

FIG. 1.

FIG. 2.

FIG. 3.
